UNITED STATES PATENT OFFICE.

BYRON J. PEPPER, OF FORT WAYNE, INDIANA, ASSIGNOR TO S. F. BOWSER & COMPANY, INC., OF FORT WAYNE, INDIANA, A CORPORATION OF INDIANA.

PUMP.

Original application filed April 23, 1921, Serial No. 463,848. Divided and this application filed December 20, 1923. Serial No. 681,791.

My invention relates to pumps and has for one of its objects the provision of a pumping mechanism having a housing which encloses all of the rest of the device.

5 A further object is the provision of a pumping mechanism having a pumping unit with a cylinder, plunger, plunger rod, and valves all detachable as a unit without disturbing the rest of the mechanism.

10 A further object is the provision of a pumping mechanism in which the valves are quickly and easily accessible for regrinding or repairing.

A further object is the provision of a pumping mechanism arranged for pumping a fluid at substantially a constant pressure.

15 A further object is the provision of a pumping mechanism in which the pressure in the discharge line will automatically stop the pump when a pressure above a predetermined pressure is obtained in said discharge line.

20 A further object is the provision of a pumping mechanism in which the operating parts are mounted in an oil chamber so as to run in 25 oil.

A further object is the provision of a pumping device adapted to pump a plurality of separate fluids.

25 A further object is the provision of means for automatically stopping the device when a predetermined quantity of liquid is pumped.

30 A still further object is the provision of a pumping mechanism which is applicable for a variety of forms of power driving mechanism.

35 Other objects will appear hereinafter.

This application is a division of my co-pending application, Serial No. 463,848, filed April 23, 1921, for an improvement in pumps 40 and which became Patent No. 1,559,365, granted October 25, 1925.

45 Embodiments of my present invention are illustrated in the accompanying drawings, forming a part of this specification, and in which—

Fig. 1 is a central section of a pumping device embodying my invention;

Fig. 2 is an enlarged vertical section of a pressure regulating valve;

Fig. 3 is a view similar to Fig. 2 but showing 50 the pressure regulating valve adapted for stopping the pumping mechanism; and

Fig. 4 is a view similar to Fig. 1, except that the pumping mechanism is arranged to pump 55 two separate liquids.

Referring more particularly to the accompanying drawings and as also clearly shown in my Patent No. 1,559,365, above identified, I have indicated a base member 20, which in the present instance is a casting, but may be 60 formed in any desirable manner. Resting on the base 20 is a housing 21, and this housing is also indicated as being a casting in the present instance, but may be formed in any desirable manner or number of parts. The housing 65 21 is indicated as having ears 22 secured to base 20 by cap screws 23, or their equivalent.

I preferably provide the housing 20 with openings 24 on its lateral sides, and these openings 24 are closed by plates 25 secured by 70 screws 26, or their equivalent. By removing the plates 25 the pump cylinder mechanism may be accessible.

Across the upper portion of the housing 21 I provide a partition 27, which in the present 75 instance is somewhat V-shaped in cross-section, as clearly indicated in Fig. 1. The chamber 28 above partition 27 is a receptacle for oil or other lubricant and also is a chamber in which the cranks and connecting rods 80 for operating the pumps are mounted. By mounting the cranks, etc. in oil in this chamber an effective lubricating means is provided which requires practically no attention after once filled with lubricant.

The top of the housing 21 may be open 85 with a plate 29 closing it when so desired so as to obtain access to the top of chamber 28. I also preferably provide the ends of chamber 28 with openings which are closed by plates 30. These plates 30 may be secured by screws 31, or in any other desirable manner.

Attached to the inner sides of plates 30 are bearings 32 in which a crank shaft 33 is journaled. I have indicated the bearing 32 as 90 being formed integral with the plates 30, but said bearings may be arranged in chamber 28 in any desirable manner.

One end of crank shaft 33 which extends from the chamber 28 is a fixed pulley 34 and a loose pulley 35. A belt, not shown, may engage said pulleys for transmitting power to the device.

In the device shown in Fig. 1 I have indicated the crank shaft 33 as having two cranks and connected to each is a connecting rod 36 which is pivoted to a sliding rod 37. Each 10 of the rods 37 is mounted for sliding in a bearing 38 adjacent crank shaft 33 and a stuffing box 39 at the partition 27. The lower ends of the rods 37 are attached to the pump piston rods.

Attached to the top of base 20 in any desirable manner, such as by cap screws 40 are housings 41 which enclose two chambers 42 and 43. Chamber 42 as better illustrated in my above identified Patent No. 1,559,365 is in 20 communication with the upper end of the pumping cylinder, and chamber 43 is in communication with the lower end of said cylinder. The chamber 42 is divided from chamber 43 by vertical partitions 45. In each of 25 chambers 42 and 43 is an intake valve 46 and a discharge valve. The intake valves 46 are in communication with an intake chamber 48 in base 20 and chamber 48 connects with a suction pipe 49, see Fig. 4, and the 30 latter is connected to some source of liquid to be pumped, not shown.

Also, in base 20 is a discharge chamber 50 which communicates with the upper sides of discharge valves and is also connected with 35 a discharge pipe into which the liquid is pumped. Mounted in the pumping cylinder is a piston having a piston rod 53 extending up through a stuffing box 54 and connected with rod 37 by a pin 55. It will be noted that when piston 52 is moved downwardly in 40 the pumping cylinder the intake valve 46 in chamber 42 will rise to permit a liquid to enter said cylinder, and upon the upward movement of piston 52 said valve 46 will be 45 closed and the discharge valve in said chamber will be raised by the liquid and the latter pass out into discharge passage 50. In these same movements of the piston the downward stroke of the latter forces liquid out of the lower end of pumping cylinder and through the discharge valve into discharge passage 50, and the upward stroke of said piston will draw liquid from chamber 48 through valve 46 in chamber 43 to the lower end of the 55 cylinder. Thus, the piston draws in liquid at one side thereof and discharges liquid at the other side thereof at each stroke. The valve 46 and the discharge valve are substantially alike and mounted in similar manners 60 as will more fully appear from my above-noted patent. The housing 41 is provided with threaded openings for said valves and in each opening is a cap 56 which has a guide on its lower side. In the guide is a stem 65 on one of said valves 46 or the discharge

valve. Said valves are maintained normally closed by compression springs. It will be apparent that the mounting and arrangement of the valves may be varied without departing from my invention.

The chamber 48 has a part extending around to the end of base 20 over a similar extension of chamber 50. A valve 60 controls an opening between said passages, said arrangement being clearly indicated in Fig. 1. Fitted in the base 20 is a housing 61 which has a guide 62 therein. In the guide 62 is the stem 63 of valve 60 arranged so that the latter may slide vertically to control the opening between chambers 48 and 50. Above guide 62 in housing 61 is an enlargement 64 which slides easily in the bore of housing 61, and pressing on the upper side of enlargement 64 is a compressing spring 65 which normally holds valve 60 closed. An adjustable member 66 is threaded in the housing 61 for varying the tension of spring 65. When it is desired to provide a pump which will pump a liquid, delivering it at a desired pressure, a relief valve, such as that just 90 described, and as indicated in Fig. 2, may be arranged to operate valve 60.

When it is desired to have the pump stopped when a pressure exceeding a predetermined pressure is obtained in chamber 50, a control mechanism, such as indicated in Fig. 1, is arranged to control the valve 60. In this arrangement the enlargement 64 has a rod 67 extending up through the top of housing 61 through a stuffing box 68 and provided with an adjustable nut or bumper 69 at its top. The nut 69 engages an arm 70 on a stirrup 71 which is pivoted on a shaft 72. The shaft 72 is journaled in a suitable part of housing 21 and has fixed thereon a cam 73. The cam operates against a roller 74 pivoted as at 75 on a horizontally sliding rod 76. The rod 76 carries a belt shifter 77 adapted to shift the belt back and forth between pulleys 34 and 35. A spring 78 tends to normally hold the belt shifter in a position to hold the belt on loose pulley 35. On the shaft 72 is fixed a lever 79 so that when it is desired to throw the pump into operation, the operator manually moves lever 79 from its position indicated in dotted lines in Fig. 1 to its position indicated in full lines in Fig. 4. This moves cam 73 against roller 74 and the latter moves rod 76 against the influence of spring 78 and carries the belt shifter 77 along to shift the belt from loose pulley 35 to tight pulley 34, thus placing the pump in operative condition. When a pressure exceeding a predetermined pressure is obtained in chamber 50, such pressure raises valve 60 against the influence of spring 65 and swings the stirrup 71 on shaft 72, and this swinging of the stirrup moves cam 73 upwardly a sufficient distance to dislodge roller 74 from a depression 80 in said cam 73. As soon as the roller 74 130

moves out of depression 80 spring 78 moves rod 76 carrying the belt shifter over to shift the belt back to the loose pulley 35 thereby stopping the pump.

- 5 I have provided a means whereby the pump will, when it has pumped a predetermined quantity, be shut off automatically. To this end a pin is provided in a disc 82 on a screw 83. Secured to the back of disc 82 is a 10 ratchet wheel and the ratchet wheel is operated by two pawls which are pivoted to a plate and the latter pivoted about the screw 83. The lever 88 is pivoted and operated by a link 90. Said link 90 has an elongated slot 15 91 therein engaging pin 55 on pump piston rod 53. The arrangement is such that when the pin 55 moves upwardly it engages the top of slot 91 moving lever 88 a short distance, and upon the downward movement of pin 55 20 the latter engages the bottom of slot 91 moving the lever 88 and consequently the plate in the forward direction.

On a suitable part of plate 25 or other portion of the casing I provide markings 96 indicating gallons or other units pumped by the pumping mechanism. A portion of the housing or plate 25 has a circular opening 97 through which a pointer 98 extends. The pointer 98 is secured by the screw 83 and a 30 screw 99 on the face of disc 82. A slot may be provided in the pointer 98 engaging screw 99 so that the relation between pointer 98 and disc 82 may be varied slightly when so desired. With this arrangement when it is 35 desired to pump a predetermined quantity of liquid, we will say five gallons for instance, the operator moves the pointer 98 so that it points to the notation of "5" of graduations 96. Then upon throwing the pump into operation by moving lever 79 the pump will 40 operate until the piston rod 53 causes the disc 82 to be moved until pointer 98 reaches the notation "50", which is also the zero or setting point. When the pointer has reached 45 this position; pin 81 will engage a projection 101 on stirrup 71 thereby lifting cam 73 high enough to disengage roller 74 from the depression 80 in said cam, at which time the spring 78 will move the belt shifter over so 50 as to move the belt from pulley 34 to pulley 35 thereby stopping the device. It will therefore be seen that the pump may be stopped by hand by the operator manually moving lever 79 into a position indicated in 55 Fig. 1. The pump may be stopped by the discharge line being closed which will increase the pressure in passage 50 and thereby cause valve 60 to trip cam 73 to stop the device. The device may also be stopped when 60 a predetermined quantity of fluid has been pumped by the pin 81 being forced against the inclined surface 101 of stirrup 71 which raises cam 73 thereby permitting spring 78 to move the belt shifter.

65 In Fig. 4 I have indicated the pumping

mechanism as arranged to pump two entirely separate liquids. In this form of the device the base 20 is provided with two separate chambers 48 and 50 divided by suitable partitions so that each pumping cylinder of 70 the two indicated, pumps a separate liquid. The crank shaft is also indicated as being two separate crank shafts, and each crank shaft driven by a separate set of pulleys 34 and 35. Each of the pulleys may have its set of belt-shifting mechanism, such as already described, so that one pump may be stopped independently of the other in any of the ways already mentioned. In such an arrangement the automatic stopping device on the left-hand side of Fig. 4 will be changed only sufficient to adapt it for the left-hand side instead of the mechanism already described for the right-hand side.

In Figures 1 and 4 I have represented the 85 casing of the machine of substantially the same form and it is an advantageous feature to arrange the casing so that a customer may select any form of driving means he desires. In this connection it will be noted that the 90 end plates 30 are the only parts necessary to vary for the different forms of driving means. Also, the same casing will enclose the double pump mechanism shown in Fig. 4, as well as the single form shown in Fig. 1. The only 95 change necessary is the mounting for the crank shaft and the arrangement of the chambers 48 and 50 in the base. Of course where belt-shifting stopping mechanism is used then two sets of these would be needed in 100 the form shown in Fig. 4.

The pumping unit which comprises a pump cylinder, its piston, piston rod and valves mounted in the casing 41 is an integral part and can be removed from the device by removing screws 40 and pin 55. This is an important feature since with this arrangement the pumping units may be easily removed for repairs or adjustment when so desired. Another important feature is the mounting of 105 the discharge valves at the highest points or in the top walls of the chambers 42 and 43 so that there is no chance for air or gases pocketing in the pump element.

The quantity notations 96 which cooperate 110 with the pointer 98 are shown in the drawings as indicating 50 gallons, but it will be understood that by varying the size of the cylinders or the driving connection any desired number of gallons may be indicated. 115 To set the device for pumping a desired quantity the pointer 98 is moved manually clockwise until it points to the required number and at which time pin 81 will engage inclined surface on the stirrup 71 to stop the driving mechanism as above referred to.

I claim:—

1. A pump comprising a base having intake and discharge passages therein; a bypass valve in said base connecting said intake 130

and discharge passages; a pumping unit connected with said intake and discharge passages; and means associated with said valve for normally maintaining the latter closed, 5 said means being adapted to yield upon pressure in said discharge passage exceeding a predetermined pressure.

2. A pump comprising a base having intake and discharge passages therein; a pumping unit attached to said base and having communication with said intake and discharge passages; a valve in said base connecting said intake and discharge passages; and a spring tending to hold said valve 15 closed.

3. A pump comprising a pumping unit having intake and discharge passages associated therewith; a pump operating means connected with said pumping unit; a valve 20 connecting said intake and discharge passages; means having a predetermined force for maintaining said valve closed and adapted to yield upon the pressure in said discharge passage exceeding a predetermined 25 pressure to open said valve; and a connection between said valve and said pump operating means for rendering the latter inoperative.

4. A pump comprising a casing; a pump operating shaft mounted in the casing; a 30 pump unit in the casing connected with said shaft and having intake and discharge passages associated therewith; tight and loose pulleys on said shaft; a belt shifter mounted in said casing; a spring tending to move the 35 belt shifter toward the loose pulley; a catch adapted for engagement with said belt shifter; and a valve in said discharge passage connected with said catch.

5. A pump comprising a pumping unit 40 having intake and discharge passages associated therewith; a valve connecting said intake and discharge passages; a spring tending to hold said valve closed; a crank shaft operatively connected with said pumping 45 unit; crank shaft operating means connected with said crank shaft; and means connected with said valve for rendering the crank shaft operating means inoperative.

6. A pump comprising a pumping unit having intake and discharge passages associated therewith; a crank shaft connected with said pumping unit; a valve connecting said intake and discharge passages; a spring normally holding said valve closed, tight and loose 55 pulleys on said crank shaft; a belt shifter associated with said pulleys; a spring tending to move said belt shifter toward said loose pulley; a catch on said belt shifter; and a member attached to said valve and engaging 60 said catch adapted to hold the belt shifter adjacent said tight pulley.

7. A pump comprising a pumping unit having a discharge passage associated therewith; a valve in said discharge passage; a

shaft connected with said pumping unit; tight and loose pulleys on said shaft; a rod having its axis substantially parallel with said shaft and mounted for longitudinal movement; a belt shifter on said rod; a spring tending to move said shaft in one direction; 70 a roller pivoted on said shaft; a cam engaging said roller and holding the rod against the influence of said spring; and means associated with said cam and valve for moving the cam upon movement of said valve to effect 75 shifting the belt shifter.

8. A pump comprising a pump operating shaft; pulleys on said shaft; a rod slidably mounted; a belt shifter on said rod; a roller on said rod; a cam having a depression therein engaging said roller; pump operable means for disconnecting said roller from said depression; and a spring associated with said rod for moving the belt shifter in one direction. 80

9. Control mechanism for a pump comprising a pump shaft; belt pulleys on said shaft; a rod slidably mounted; a belt shifter on said rod; a roller on said rod; a spring associated with said rod and tending to move the latter 90 in one direction; a cam having a depression therein adapted to engage said roller and hold said rod against the influence of said spring; and means adapted to move said cam to disengage said depression from said roller and 95 permit the spring to move said rod.

10. Control mechanism for a pump comprising a belt shifting rod; a spring associated with said rod for moving the latter 100 in one direction; means for holding the rod against the influence of said spring; and means for rendering the means holding the rod against the influence of the spring into inoperative condition.

11. A pump comprising a pumping unit 105 having a reciprocatory member therein; a power shaft operatively connected with the pumping unit; a belt shifter associated with said power shaft; a spring adapted to move the belt shifter in one direction; a catch for holding the belt shifter against the influence 110 of said spring; a trip for engaging said catch from said belt shifter; and means operable by the pump for operating said trip.

12. A pump comprising a pumping unit 115 having a discharge passage associated therewith; a drive shaft connected with said pumping unit; a belt shifter associated with said drive shaft; a spring tending to move said belt shifter in one direction; means for holding the belt shifter against the influence of 120 said spring; and means operable by said valve for rendering the means holding the belt shifter against the influence of said spring in inoperative condition.

13. A pumping unit comprising a reciprocatory member; a power shaft connected with said pumping unit; a belt shifter associated

with said power shaft; resilient means tending to move said belt shifter in one direction; a cam holding the belt shifter against the influence of said spring; a stirrup engaging 5 said cam; and a pin operable by the reciprocating member of said pumping unit adapted to engage said stirrup and move the cam out

of operative engagement with said belt shifter.

In testimony whereof I have signed my 10 name to this specification on this 12th day of December A. D. 1923.

BYRON J. PEPPER.
